UNITED STATES PATENT OFFICE.

GEORGE S. HENSEL, OF PHILADELPHIA, PENNSYLVANIA, ASSIGNOR TO THE HENSEL, COLLADAY COMPANY, OF PENNSYLVANIA.

DESIGN FOR A SKIRT OR GARMENT PROTECTOR.

SPECIFICATION forming part of Design No. 32,975, dated July 17, 1900.

Application filed June 18, 1900. Serial No. 20,771. Term of patent 14 years.

To all whom it may concern:

Be it known that I, GEORGE S. HENSEL, a citizen of the United States, residing in the city and county of Philadelphia, in the State 5 of Pennsylvania, have invented and produced a new and original Design for a Skirt or Garment Protector, of which the following is a specification, reference being had to the accompanying drawings, forming part thereof.

The leading feature of my design for a skirt or garment protector is a body having a head, with ribs extending in the vertical direction thereof and a brush pendent from the lower edge of said head.

Figure 1 represents a side elevation of a piece of skirt or garment protected embodying my design. Fig. 2 represents a vertical section thereof on line X X, Fig. 1. Fig. 3 represents a top edge view thereof.

In the drawings, A designates a piece of a 20 skirt or garment protected, the same being composed of the head B and brush C. On the side of the head are the ribs D, which extend parallel in the vertical direction of the piece, and the brush depends from the lower edge 25 of said head.

Having described my invention, what I claim as new, and desire to secure by Letters Patent, is—

The design for a skirt or garment protector 30 substantially as shown and described.

GEORGE S. HENSEL.
